United States Patent Office

Des. 212,118
Patented Aug. 27, 1968

212,118

BROOCH OR SIMILAR ARTICLE

Ronald E. Tomchin, 31-33 Debevoise St.,
Brooklyn, N.Y. 11206

Filed Nov. 15, 1967, Ser. No. 9,419

Term of patent 14 years

(Cl. D45—19)

FIG. 1

FIG. 2

FIG. 3

FIG. 4

FIG. 5

FIG. 6

FIG. 1 is a front elevational view of a brooch or similar article showing my design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

The dominant features of my design reside in those portions shown in full lines on the drawing, the conventional gems being shown in broken lines.

I claim:

The ornamental design for a brooch or similar article, as shown and described.
